REGISTRY AND SIDE GUIDE MARKER

Aaron Marsden, Brooklyn, N. Y.

Application January 24, 1950, Serial No. 140,306

2 Claims. (Cl. 101—373)

1

This invention relates generally to printing members and more particularly to a registry and side guide marker for use in or on a type chase.

Devices of this general type are known in the art but are usually characterized by various disadvantages which make them impractical in use. Among these disadvantages are an excessive cost, an unwieldiness in use, a limited number of applications in general job printing, and the necessity of maintaining an unreasonable inventory of parts.

As a result, the job printer has resorted to makeshift arrangements for marking sheets for registry and side guide purposes which involve the fashioning of markers from bent wires, the using of nails in wooden furniture, etc. These improvisations are so time consuming and too often inaccurate as to be entirely unsatisfactory and a source of real annoyance.

Accordingly, the chief object of the present invention is to provide a registry and side guide marker for use with type chases in job printing which may be readily inserted in any desired position in or on a chase and quickly and accurately adjusted in that position.

Another important object of the present invention is to provide a registry and side guide marker having a printing surface which will be exactly "type high" when inserted within or on a chase.

A further important object of the present invention is to provide a registry and side guide marker which may be inserted in or on a chase during lock-up and which will conform with the furniture being used.

A still further important object of the present invention is to provide a registry and side guide marker which requires a minimum of space within a chase, which is rugged and of long life, and which is economical to manufacture.

Other objects and advantages of the invention will become apparent during the course of the following description.

In the drawings I have shown one embodiment of the invention. In this showing:

Figure 1 is a fragmentary top plan view of the register and side guide marker comprising the present invention in one of its operative positions in a type-laden regular chase;

Figure 2 is an end elevation thereof;

Figure 3 is a fragmentary vertical sectional view taken on the line 3—3 of Figure 1;

Figure 4 is a fragmentary vertical sectional view taken on the line 4—4 of Figure 3;

Figure 5 is a perspective view of the register marker comprising the invention;

Figure 6 is a top plan view of the point marking screw forming a part of the invention as a whole; and

Figure 7 is a fragmentary perspective view of a stack of printed sheets each of which bears the printed dot of the register marker.

Referring to the drawings, the registry and side guide marker is indicated as a whole by numeral 10 and comprises a flat L-shaped bar having legs 12 and 14. The leg 14 is bent 90° with respect to the leg 12 (Figure 5) so as to project laterally from the upper edge of the latter.

A slot 16 is formed in the face of the leg 14 and extends longitudinally thereof for the reception of a screw 18 which may be temporarily fixed in any position along the length of the slot by means of a nut 20. A shoulder 22 is formed on one surface of the screw head and projects within and conforms with the sides of the slot 16 to prevent rotation of the screw when the nut is tightened.

The conventional taper at the end of the threads of the screw 18 is centrally flattened as at 24 so as to print a small but readily visible round dot when the marker is serving its function in the type chase C during printing operations. The marker 10 is formed of high grade steel stock $\frac{23}{100}$ inches or 2 points thick which enables it to be locked outside the chase as well as inside. Thus the marker can be positioned anywhere within the chase or over the chase proper to readily print a guide mark in the desired location on a printed page.

When it is desired to use the marker 10 within the chase, the leg 12 is clamped between wooden or metal furniture F or between furniture and type during lock-up with the screw 18 properly positioned transversely of the chase. The nut 20 is then loosened so that the screw may be properly positioned longitudinally with respect to the page by movement along the slot 16 whereupon it is fixed in proper position by simply tightening the nut with the fingers. Obviously, when the range of the slot does not permit proper positioning of the screw, the marker 10 must be shifted as a whole to permit it.

When it is desired to use the marker 10 on the chase proper (Figures 1—4 incl.), the leg 12 is positioned against the bottom inner edge of the chase C with the head of the screw 18 resting on the chase. The height of the screw is such that the dot printing surface 24 is exactly "type-high," that is exactly as high as the surface of the type locked up in the chase (Fig. 3). Two sizes of screws are provided as heights vary on

the chase proper. As before, the marker is properly adjusted transversely of the chase before lock-up and the screw may then be properly positioned along the slot 16.

During printing operations, the marker prints a round dot at the edge of the printed page in accordance with its position which dots serve as a means for checking registry and also as a guide for the bookbinder. Figure 7 shows a stack of printed pages each bearing a single dot in perfect register so as to form, in effect, a vertical line 30. The bookbinder is thus aware that the correct gripper guide is along the line 32. It will be readily apparent that if the printed dots do not form a straight line, the stack of printed sheets is not in proper alignment.

The registry and side guide marker forming the present invention thus eliminates prior time wasting and inaccurate methods of fashioning registry checking means by providing a handy, rugged device which conforms with printing type, furniture and chases and which may be easily inserted during lock-up and readily and accurately adjusted without unnecessary loss of time.

It is to be understood that the form of the invention herewith shown and described is to be taken as a preferred example of the same and that various changes in the shape, size and arrangement of parts may be resorted to without departure from the spirit of the invention or the scope of the subjoined claims. 30

I claim:

1. A type measure for printing registry and side guide marks on printed sheets comprising an angle shaped bar having a leg adapted to be clamped with type in a chase, the other leg of said bar being bent out of the plane of said first leg and having a slot formed therein ex-

tending angularly with respect to said first leg, a screw including a printing surface and being non-rotatably and slidably mounted in said slot, and means mounted on said screw for securing it to said bar in any position along said slot.

2. A type member for printing registry and side guide marks on printed sheets comprising an angle shaped bar having a leg adapted to be clamped with type in a chase, the other leg of said bar being bent out of the plane of said first leg and having a slot formed therein extending angularly with respect to said first leg, a screw including a printing surface and being non-rotatably and slidably mounted in said slot, and means mounted on said screw for securing it to said bar in any position along said slot, said bar being the thickness of a conventional type spacing member to enable its substitution therefor.

AARON MARSDEN.
